UNITED STATES PATENT OFFICE.

HOWARD C. RASH AND LEON C. RASH, OF SALINA, KANSAS, ASSIGNORS TO THE NATURAL BODY BRACE COMPANY, OF SALINA, KANSAS, A CORPORATION OF KANSAS.

ABDOMINAL AND BACK SUPPORTER.

SPECIFICATION forming part of Letters Patent No. 708,402, dated September 2, 1902.

Application filed April 1, 1902. Serial No. 100,956. (No model.)

To all whom it may concern:

Be it known that we, HOWARD C. RASH and LEON C. RASH, citizens of the United States, residing at Salina, in the county of Saline, 5 State of Kansas, have invented certain new and useful Improvements in Abdominal and Back Supporters, of which the following is a description, reference being had to the accompanying drawings, and to the letters of reference marked thereon.

Our invention relates to combined abdominal and back supporters.

The objects of the invention are to provide a combined abdominal and back supporter 15 of simple construction capable of being easily applied and having its parts relatively adjustable to fit different persons of different shape and size; also to provide such a supporter with shoulder-straps which may be 20 readily removed when desired; to provide for the effectual retaining of the pads in their adjusted positions on the wearer. These objects we accomplish by the mechanism shown in the accompanying drawings, in which—

25 Figure 1 is a front perspective of our improved abdominal and back supporter with the shoulder-braces applied with the front or abdominal plate closed. Fig. 2 is a similar view looking from the rear with the front plate 30 in the closed position. Fig. 3 is an enlarged view of the front or abdominal plate removed. Fig. 4 is a detail sectional view through one 35 of the hip-springs and back-springs at their point of connection; and Fig. 5 is a section on line 5 5, Fig. 3.

A designates the sectional adjustable front or abdominal plate, of any suitable form and material. This plate is formed in two sections A' A², overlapped at their inner reduced ends and held in contact by upper and lower guide-flanges a a, formed by folding the upper and lower edges of section A² to form guideways for the upper and lower outwardly-projecting flanges A³ of the reduced 40 inner end of section A'. This reduced portion of section A' is provided with an open slot a', through which extends the screw a², mounted in the section A² and provided with a bail-nut a³, which bears on the outer face 45 of the section A', and so clamps the two sec-

tions together. The section A² is further formed with a T-shaped guide-rib A⁴, passing through the slot a', with its outer flange or head portion overlying the section A' at opposite sides of said slot. Thus the two 55 sections A' A² will be held in sliding connection without any lateral or twisting movement. By loosening this nut the sections A' A² may be adjusted in or out, so as to shorten or lengthen the plate, and when the nut is 60 loosened the plate-sections may be separated. The flange A³ extends, preferably, entirely around the margin of the front plate A and is cut away at the upper corners of the plate, as shown at a⁴. 65

B B are the curved hip-straps, formed of ribbon, steel or other suitable spring metal. These hip-straps are pivoted at their front ends to the respective plate-sections A' A² and pass out through the cut-away places a⁴ in the 70 flange A³, the ends of the flange thus forming stops a⁵ a⁵ to limit the upward movement of the said hip-straps. The rear ends of the hip-straps B B are each provided with a plurality of round holes b b, through which pass 75 the round unthreaded portions of the screws b', which carry the S-shaped back-springs C, said screws being provided with bail-nuts b² on their outer ends and being squared where they pass through the square openings c in 80 back-springs C. Thus freedom of movement is allowed between the hip-springs and the back-springs to accommodate movements on the part of the wearer, while the screws are held from turning in the 85 back-springs C by the squared openings and squared portions of the screws b'. By changing the position of the screws b' to different holes b the hip-straps may be lengthened or shortened. The back-springs C C are each 90 provided with a plurality of the square openings c c, so that they may be raised or lowered, and so bring the round back pads or plates D D, secured to their upper and lower ends, into proper position relative to the parts 95 of the body to be pressed upon. The upper pads D are connected by inelastic webbing d, while the lower pads D are similarly connected by straps d'. To each lower back plate or pad is secured 100

by the same rivet that secures it to its spring a buckle e or equivalent adjusting device, which carries a perineal strap E . These perineal straps E are provided at their forward ends with slides e' , each having a key-hole-slot e^2 to engage headed studs e^3 , projecting from the front-plate sections $A' A^2$, respectively. These headed studs e^3 also serve to prevent the hip-straps b from swinging down too far.

The webbing d , which connects the upper back-pads D , is preferably the middle portion of an inelastic belt F . In any event the upper back-pads are secured to a belt F , which is adapted to pass around the waist and be secured in front, above and independent of the front plate A , by a buckle or other suitable means. It will be seen that this belt will hold the back-pads D from working up and down out of position and alone or in connection with the perineal straps will securely hold the pads as adjusted on the wearer.

The support so constructed may be readily applied by simply opening the front plate and passing the hip-straps around from the back to the front and then adjusting the sections $A' A^2$, properly tightening their securing-nut, and then bringing the perineal straps up from the rear and securing them to the studs e^3 .

Buckles $g g$ are also secured to the upper back-pads $D D$, and to these buckles are adjustably connected the lower ends of the elastic straps $G G$, which form the shoulder-brace. These straps $G G$ are connected by a short transverse strap g' , having buckles g^2 at its respective ends, to which the free ends of the straps G are connected to form the shoulder-loops.

It will be seen that by having our front plate A separable the back-pads may be permanently connected, as it is only necessary to open the front plate or pad and unbuckle the waistband or belt F in order to apply or remove the supporter.

Having thus described our invention, what we claim as new, and desire to secure by Letters Patent, is—

1. The front plate formed in two separable sections overlapped at their adjacent ends to form a rigid sliding connection, and means for securing the two sections separably together in their adjusted positions; substantially as set forth.

2. The front or abdominal plate or pad formed in two separable sections, one section having guides, and the other section having an open slot, and in sliding connection with said guides, and a set-screw extending through one section and through the said open slot in the other section; substantially as described.

3. The combination with the front plate provided with a marginal flange cut away at its upper corners, of the hip-straps pivoted at their forward ends to the said front plate and extending through the said cut-away portions, and headed studs projecting from the front plate in the path of the lower edges of the

hip-straps to prevent them from dropping down too low.

4. A combined abdominal and back supporter, comprising curved spring hip-straps, an abdominal plate secured to the front ends of said hip-straps and formed in two separable rigidly-connected sections, and a back-supporting device connecting the rear ends of said hip-straps; substantially as described. 70

5. A combined abdominal and back support, comprising curved spring hip-straps, an abdominal plate secured to the front ends of said hip-straps and formed in two separable sections, back-springs secured between their ends to the rear ends of said hip-straps, back-pads secured to the upper and lower ends of the back-springs, a belt connecting the two upper back-pads, and adapted to pass around the waist to be connected at its ends above and independent of the abdominal plate, and a connection between the lower back-pads; substantially as described. 80

6. A combined abdominal and back supporter, comprising curved spring hip-straps, an abdominal plate secured to the front ends of said hip-straps and formed in two separable and adjustably-connected sections sliding one upon the other, back-springs adjustable laterally and vertically between their ends on the rear ends of the hip-straps, connected back-pads on the lower ends of the back-springs, back-pads on the upper ends of the back-springs, and a waistband or belt secured at its middle to said upper back-pads, and adapted to be fastened together at its ends above and independent of the abdominal pad; substantially as described. 90

7. A combined abdominal and back supporter, comprising the curved spring hip-straps, having a series of round holes in their rear ends, a sectional separable abdominal plate connecting the front ends of the hip-straps, back-springs at the rear ends of the hip-straps, provided with a series of square apertures, screws passed through said holes and apertures, and having squared portions for the said square apertures, and smooth round portions for the said round holes, nuts 105 on the outer ends of the screws, connected pads on the lower ends of the back-springs, upper pads on the upper ends of the back-springs, and a waistband or belt connecting the upper back-pads, and adapted to be fastened at its ends above and independent of the abdominal plate; substantially as described. 110

8. A combined abdominal and back supporter, comprising the flanged front plate 125 formed in two separable sections with its flange cut away at its upper corners, a headed stud on each section, curved spring hip-straps pivoted at their front ends to said sections and extending through said cut-away portions, back-springs adjustably connected to the rear ends of the hip-straps, connected pads on the lower ends of the back-springs, pads on the upper ends of the back-springs, 130

a waistband or belt connecting said upper plates or pads at its middle, and adapted to encircle the waist above the abdominal plate or pad, and perineal straps connected to the 5 lower back-pads and provided at their ends with slides having keyhole-slots to engage the headed studs on the abdominal plate; substantially as described.

9. A combined abdominal, back and shoulder supporter or brace, comprising the curved spring hip-straps, the separable abdominal plate at the front ends of the hip-straps, the back-springs connected to the rear ends of the hip-straps, the lower connected back-pads on 15 the lower ends of the back-springs, the perineal bands connecting the lower back-pads with the abdominal plate, the waistband connecting the upper back pads or plates, and adapted to pass around the waist above and 20 independent of the abdominal plate and the shoulder-straps connected at their lower ends to the upper back-pads; substantially as described.

10. A combined abdominal and back supporter, comprising the curved spring hip-straps having a series of round holes in their rear ends, a sectional separable abdominal

plate connecting the front ends of the hip-straps, back-springs at the rear ends of the hip-straps provided with a series of square 30 apertures, screws passed through said holes and apertures and having squared portions for the said square aperture and smooth round portions for the said round holes, nuts on the outer ends of the screws, pads on the 35 lower ends of the back-springs and pads on the upper ends of the back-springs.

11. A combined abdominal and back supporter, comprising curved spring hip-straps, an abdominal plate secured to the front ends 40 of the hip-straps and formed in two separable rigidly-connected sections, back-supporting springs at the rear ends of the hip-straps, means whereby the back-springs may be adjusted along the rear ends of the hip-straps 45 and also vertically on the hip-straps, and pads carried by the ends of the said back-springs.

In testimony whereof we affix our signatures in presence of two witnesses.
